US00D791591S

(12) **United States Design Patent** (10) **Patent No.:** **US D791,591 S**
(45) **Date of Patent:** **** Jul. 11, 2017**

(54) **CLOSURE**

- (71) Applicant: **Silgan White Cap LLC**, Downers Grove, IL (US)
(72) Inventor: **Gary Berge**, Crystal Lake, IL (US)
(73) Assignee: **Silgan White Cap LLC**, Downers Grove, IL (US)
(**) Term: **15 Years**
(21) Appl. No.: **29/564,416**
(22) Filed: **May 12, 2016**

Related U.S. Application Data

- (62) Division of application No. 29/507,935, filed on Oct. 31, 2014, now Pat. No. Des. 760,081.
(51) **LOC (10) Cl.** **09-07**
(52) **U.S. Cl.** **D9/452**

CLAIM

I claim the ornamental design for a closure, as shown and described.

DESCRIPTION

FIG. 1 is a top perspective view of a closure showing the claimed design;

FIG. 2 is a front view of the claimed design of FIG. 1;
FIG. 3 is a right side view of the claimed design of FIG. 1;
FIG. 4 is a rear view of the claimed design of FIG. 1;
FIG. 5 is a left side view of the claimed design of FIG. 1;
FIG. 6 is a top view of the claimed design of FIG. 1;
FIG. 7 is a bottom view of the claimed design of FIG. 1; and,
FIG. 8 is a bottom perspective view of the claimed design of FIG. 1.

The ornamental design which is claimed is shown in solid lines in the drawings.

In the drawings, the broken lines showing portions of a closure depict environment and form no part of the claim.

1 Claim, 8 Drawing Sheets
